UNITED STATES PATENT OFFICE.

BURWELL S. CUTLER, OF BUFFALO, NEW YORK.

DESIGN FOR A CHAIR.

49,176.

Specification for Design.

Patented June 13, 1916.

Application filed May 8, 1916. Serial No. 96,241. Term of patent 3½ years.

To all whom it may concern:

Be it known that I, BURWELL S. CUTLER, a citizen of the United States, residing at Buffalo, in the county of Erie and State of New York, have invented a new, original, and ornamental Design for a Chair, of which the following is a specification, reference being had to the accompanying drawing, forming part thereof.

The figure is a perspective view of a chair showing my new design.

I claim:

The ornamental design for a chair, as shown.

BURWELL S. CUTLER.
